We claim the ornamental design for a tip for oral irrigator, as shown and described.

DESCRIPTION

FIG. 1 is a perspective view of a tip for oral irrigator.

FIG. 2 is a left side elevation view thereof.

FIG. 3 is a front elevation view thereof.

FIG. 4 is a rear elevation view thereof; and,

FIG. 5 is an enlarged, representative, fragmentary, cross-

sectional view thereof taken along line 5-5 in FIG. 3.

The broken line showing of the oral irrigator in FIG. 1 illustrates environment and forms no part of the claimed design. The broken lines in FIGS. 2-5 illustrate portions of the tip for oral irrigator that form no part of the claimed design.
